WILLIAM H. BROWN, OF WASHINGTON, DISTRICT OF COLUMBIA, ASSIGNOR TO HARRY
N. KOPPLE, OF PHILADELPHIA, PENNSYLVANIA

AMUSEMENT DEVICE

Application filed July 19, 1930. Serial No. 469,049.

This invention relates to amusement devices and has for an object to provide a device, the use of which will include a thrown ball, and with a second ball to be returned to the pitcher by the device under certain circumstances.

A further object of the invention is to provide a target in the representation of a ball player holding a bat, said bat being ful-
10 crumed upon the image to oscillate when hit by a thrown ball, the oscillation to continue if sufficiently intense to strike a supported ball, and return said supported ball to the pitcher of the first mentioned ball.

15 A further object of the invention is to provide an image representing a ball player, holding a bat, one part of which represented bat is oscillatable at the rear of the image, an oscillation comprising substantially a semi-circle bringing said bat into impinge-
20 ment with a ball supported at the proper height, so that said supported ball is projected from its support toward the pitcher of the first mentioned ball.

25 The invention is directed to other objects and possesses other features of novelty and advantage, some of which, together with the foregoing, will be hereinafter more fully set forth.

30 In the drawings:

Figure 1 is a perspective view seen largely from the front showing the apparatus in position, and

35 Figure 2 is a view in rear elevation of the figure mounted upon a different type of base.

Like characters of reference indicate corresponding parts throughout the several views.

40 The present invention comprises a supporting structure, here indicated as the image of a ball player, and designated as 10. The figure is wholly unimportant to the present invention, except as lending a degree of realism to the use of the device.

45 This support or image 10, is preferably constructed of material sufficiently rigid to withstand shocks from a pitched ball, and such material may well be a board or a plank, properly contoured as may meet the fancy
50 of the maker or user, as for instance, the out-

line of a human figure, and the front will be painted or otherwise decorated to analogize a ball player in costume.

At the rear of this figure, which will be substantially a plane surface, a shaft 11 will be mounted to oscillate. Such mounting may be by the use of clips 12 and 13, with a supporting lug 14. About the shaft 11, a spring 15 will be employed, bearing at one end, as indicated at 16, against the rear of the figure and its opposite end 17, secured to the shaft.

At its upper end above the clip 12, the shaft 11 is enlarged and internally screw threaded as indicated at 18, such shaft 11 being substantially vertical and curved so that the threaded part 18 has its axis substantially horizontal.

Introduced into this threaded part 18, is the nipple 19, into which is inserted the bat 20 and secured therein by a pin or screw 21. Thus assembled, the bat and its nipple 19 may be removed from the connection 18. For additional realism, the front of the figure 10, will show a painted section 21 of a bat, extending to the margin of the figure, so that the actual bat 20, which is at the rear of the figure, will appear to register with the section 21 and form a continuous bat held in the hand of the figure.

At the rear of the figure is also mounted a bell 22, with clapper 23 actuated by a cord, or other means 24, connecting with the nipple 19, so that when the nipple 19 and the shaft 11 oscillate against the tension of the spring 15, from impact of a pitched ball against the bat, the bell 22 will be struck by the clapper.

Erected in spaced relation to the figure 10, is a T 25, upon which will be mounted a ball 26, the relation being such, that as the bat 20 oscillates through substantially a semi-circle, it will impinge against the ball 26, the direction of such impinging being such that the ball will be projected toward the pitcher of the original ball.

The manner of supporting the figure 10 and its associated parts, and the T 25, is elective. In Figure 2, a base comprising a bar 27, and a cross bar 28, is disclosed. This base will or may be secured to the ground by pins 29 inserted through the ends of the cross bar,

and when so erected, may serve as an amusement device upon a lawn, or the like.

For regularly constituted amusement parks or places however, a more elaborate mounting is desirable, and as shown at Figure 1, such a mounting comprises a box 30 having cleats 31 and 32 for holding respectively the figure 10 and the T 25, other cleats 33 will hold masts 34, the tops being reduced to form pins 35 which will penetrate perforations in the bar 36.

To the bar 36, a curtain 37 is attached hanging downwardly to the rear of the figure 10 and T 25, and spaced therefrom a sufficient distance to permit the oscillation of the bat 20. The bottom of the curtain 27, is provided with a bar or roller 38 which will be of sufficient length to bear at its ends against the masts 34, and preferably springs 39 will be provided to prevent undue swinging of this bar 38 under the impact of the ball or wind.

All of these several parts are designed to be disconnected as will be perfectly apparent, and all to be packed into box 30, so that the equipment is collective into the minimum space for shipment and storage. While the device may be used in a number of different ways, and strictly for play, as is intended with the device mounted as at Figure 2, it may also be used as a prize winning sport, the user being provided with a given number of balls for a pre-determined amount, and certain prizes awarded for hitting the bat, and more valuable prizes awarded for hitting the bat so as to oscillate it about to hit the ball 26, the pitcher to catch the ball when projected in his direction.

Of course, the amusement device, herein illustrated, may be modified in various ways without departing from the invention herein set forth and hereinafter claimed.

The invention is hereby claimed as follows:

1. An amusement device comprising an up-standing figure, a bat mounted at the rear of the figure to oscillate in a horizontal plane, a yielding return member for the bat, and a T positioned to support a ball in the path of oscillation of the bat, said return member continuously resisting the oscillation of the bat toward the T.

2. An amusement device comprising an up-standing figure, a shaft journaled at the rear of the figure in a vertical line, an offset from said shaft, means carried by said offset to support a bat in horizontal direction, a yielding return member embracing said shaft, and a T erected at substantially the height of the bat and on the side of the figure opposite the normal projection of the bat, said return member tending to continuously maintain the bat at the side of the figure opposite to and resist oscillation toward the T.

3. An amusement device comprising an up-

standing figure, a T at one side of the figure, a shaft journaled at the back of the figure and provided with a horizontally projected curved extremity, a bat having separable connection with said extremity and extending beyond the figure and in a horizontal direction at the side of the figure opposite the T and adapted to oscillate in a plane juxtaposed to the top of the T, a yielding return member for the shaft tending to hold the bat in said position, a sounding device carried by said figure, and means connecting the bat with the sounding device operating mechanism.

4. An amusement device comprising an up-standing figure, a shaft journaled at the rear of the figure in a vertical line, an offset from said shaft, means carried by said offset to support a bat at an angle to the vertical, a yielding return member embracing said shaft, and a T erected at substantially the height of the bat at a corresponding distance from the vertical line and on the side of the figure opposite the normal projection of the bat, said return member tending to maintain the bat at the side of the figure opposite the T.

5. An amusement device comprising an up-standing figure, a T at one side of the figure, a shaft journaled at the back of the figure and provided with a horizontally projected curved extremity, a bat having separable connection with said extremity and extending beyond the figure at an angle to a vertical, a yielding return member for the shaft tending to hold the bat at the side of the figure opposite the T, a sounding device carried by said figure, and means connecting the bat with the sounding device operating mechanism.

In testimony whereof I have signed my name to this specification.

WILLIAM H. BROWN.
